UNITED STATES PATENT OFFICE.

HAROLD P. FARIS, OF CHICAGO, ILLINOIS, ASSIGNOR TO KROEHLER MANUFACTURING COMPANY, OF NAPERVILLE, ILLINOIS, A CORPORATION OF ILLINOIS.

UPHOLSTERING.

Application filed February 27, 1928. Serial No. 257,131.

This invention relates to improvements in upholstering, and has for its principal object to provide a new form of upholstering for sofas, chairs or the like and especially the backs and sides thereof, whereby softer and more luxurious cushions may be utilized than heretofore, and also producing an improved appearance to the upholstered piece.

As heretofore constructed, standard furniture upholstering has usually consisted of a spring backing, a more or less heavy filling such as hair or the like covering the springs, and a cloth or leather covering tightly fitted over the filling so as to maintain it, and the springs, under compression. Upholstering of this general type although varying in detail of construction is utilized on backs, seats, and arms of furniture of the class herein described. In addition, separate or detachable cushions of various forms are sometimes utilized, including seat cushions of combined spring and filling structure, such as are often furnished as a part of the piece, as well as detached back rest cushions of the pillow type, which may or may not be originally furnished as a part of the piece.

In carrying out my invention, I provide an improved construction especially adapted for the back and arms, wherein separate cushion units of the loose down type are employed, but instead of being detached as heretofore, said cushions are of special form and are arranged to permanently cover the back or arms, or both, so as to become an integral part of the piece, thus retaining the general appearance of the ordinary upholstered surface, but eliminating the effects of the more or less tightly tensioned coverings thereof, and substituting therefor the softer and more luxurious effects of full cushioned yielding surfaces. Furthermore, by my improved arrangement and method of mounting the cushion units on the piece, the same may be readily "fluffed up" from time to time as required to maintain or restore their proper looseness and shape.

The invention may best be understood by reference to the accompanying drawing in which, Figure 1 is a perspective view of the upper part of a sofa constructed in accordance with my invention.

Figure 2 is an enlarged vertical section taken through the back of the piece shown in Figure 1,

Figure 3 is a detail view of a cushion form-

ing an essential part of my invention, before it is applied to the piece,

Figure 4 is a perspective view showing the method of application of the cushion to one arm of the sofa shown in Figure 1.

In the drawings, I have illustrated my invention as applied to sofa 10, having seat 11, back 12 and arms 13, 13. These parts may consist of wooden frames, with upholstering thereon, substantially as heretofore constructed. For instance, Figure 2 shows a typical section of a back portion 12, including frame members 14, backing 15, springs 16, and a front face comprising filling 17 and cover 18, all of standard upholstering construction, excepting that when my improved form of cushions are used it is not usually necessary to provide as much filling 17 as heretofore, nor to provide expensive finished or patterned coverings 18, unless it be along the edges 18^a, where such covering is exposed, as will hereinafter more fully appear.

Referring now more particularly to the especial features of novelty of my invention. I provide a series of cushions 20, 20, shown separately in Figure 3, of suitable form and shape so as to extend over the inner face of the back or arms of the piece, and secured only along the upper and lower ends thereof, as for instance by nailing said upper and lower edges along the rear of the wooden frame members 14, 14, as shown in Figure 2. The sides of the cushions 20, 20, are not secured, but are left free along opposite side edges, so as to permit free access between the cushion and the upholstering therebeneath, so that each cushion may be readily "fluffed up" or reshaped from opposite sides thereof, without removing the same from its position. This arrangement also facilitates thorough cleaning of the piece.

In the form shown, the cushions 20, 20, are preferably stuffed loosely, as for instance, with down or similar relatively light upholstering material. When utilized for the back 12 of a sofa, as shown herein, a plurality of such cushions are employed, each provided with continuous upper and lower covers 21, 22, joined by vertically extending side pieces 23, 23, so that the abutting sides of the cushions are relatively flat and fit fairly closely against each other when in final position, as shown.

The arms 13 of a sofa or chair may also be provided with my improved form of cushion.

As seen in Figure 4, the cushion 20^a, of a general form similar to the back cushions 20, 20, is shown with its upper edge loosened and turned inwardly from the arm 13, but it will be understood that when finally completed, the upper edge of the cushion 20^a will be fitted over the arm 13 and having its upper edge secured along the under edge of said arm as shown in Figure 1, but leaving the 10 sides of said cushion open at front and back.

The arrangement of cushions 20 and 20^a as described affords not only increased luxury and comfort, but gives a somewhat different appearance in line with these characteristics, 15 by reason of the fact that the edges 23, 23, of the cushions stand out from the exposed portions of the usual upholstered under-covering 18, for instance as indicated at 18^a, thus giving an invitingly luxurious appearance to the 20 piece.

While I have illustrated and described the particular embodiment of my invention as applied to sofas, it will be understood that it may also be applied to chairs and the like, and 25 that various changes and modifications may be made without departing from the spirit and scope of my invention.

I claim as my invention:

1. In combination with a piece of upholstered furniture, a cushion having relatively loose and light filling material extending across an upholstered face of said piece and secured to the latter along two opposite end edges of said cushion, but leaving the intermediate portions of said cushion unsecured so as to permit access between said cushion and said upholstered face.

2. In combination with a piece of upholstered furniture, a cushion of relatively loose and light filling material extending across an upright upholstered face of said piece and

secured to the latter along the upper and lower edges of said cushion, but leaving the side edges of said cushion unsecured so as to permit access between said cushion and said 45 upholstered face.

3. In combination with a piece of upholstered furniture, a cushion of relatively loose and light filling material extending across and over the top margin of an upright up- 50 holstered face of said piece and secured to the latter along the upper and lower edges of said cushion, but leaving the side edges of said cushion unsecured so as to permit access between said cushion and said upholstered 55 face.

4. In combination with a piece of upholstered furniture, a plurality of cushions of relatively loose and light filling material ex- 60 tends side by side across an upright up- holstered face of said piece and secured to the latter along the upper and lower edges of said cushion, but leaving the side edges of said cushions unsecured so as to permit access between each of said cushions and said up- 65 holstered face.

5. In combination with a piece of upholstered furniture, a plurality of cushions of relatively loose and light filling material ex- 70 tends side by side across an upright up- holstered face of said piece and secured to the latter along the upper and lower edges of said cushion, but leaving the side edges of said cushions unsecured so as to permit access between said cushions and said upholstered 75 face, said cushions having substantially upright side faces adapted to fit flatwise against each other when in abutting relation.

Signed at Chicago, Ill., this 23rd day of February, 1928.

HAROLD P. FARIS.
